UNITED STATES PATENT OFFICE.

FRANK C. H. STRASBURGER, OF CHICAGO, ILLINOIS, ASSIGNOR TO BOTTLEERS' SPECIALTY MANUFACTURING CO., OF CHICAGO, ILLINOIS, A CORPORATION OF IOWA.

LABELING-MACHINE.

SPECIFICATION forming part of Letters Patent No. 720,295, dated February 10, 1903.

Application filed March 20, 1902. Serial No. 99,091. (No model.)

To all whom it may concern:

Be it known that I, FRANK C. H. STRASBURGER, a citizen of the United States, residing at Chicago, in the county of Cook and State of Illinois, have invented certain new and useful Improvements in Labeling-Machines, of which the following is a specification.

My present invention relates to labeling-machines, and has particular reference to the label-supply holder and its operating means and to the paste-supply.

The principal object of this invention is to enable a much larger supply of labels to be carried by the holder than has been customary heretofore and provide that the top label in the pile shall always make proper contact with the label-carrier.

Another object is to feed the pile of labels in the holder automatically from the bottom to the top thereof and independent of the movement of the holder; and a further object of the invention is to provide a paste-supply tank for replenishing the supply of paste in the paste-pot while the latter is in operative position.

I have illustrated the invention embodied in a bottle-labeling machine of one type; but it will be understood that I do not restrict myself to the use of this invention in labeling-machines of this or any other particular variety.

In the drawings, Figure 1 is a sectional elevation of the machine with one of the side plates removed and showing the label-holder in its lowest position. Fig. 2 is a detail view of the paste-supply tank. Fig. 3 is an enlarged sectional detail view of the label-holder and support. Fig. 4 is an enlarged sectional detail view showing the feed-rod locked in its lowest position to permit the label-holder to be refilled. Fig. 5 is a similar view, but showing the pawl arranged in locking engagement with the rod to prevent it from being lowered when the label-pile contacts with the carrier. Fig. 6 shows the cam and lever devices for operating the paste-pot. Figs.

7 and 8 are top plan views, respectively, of the label holder and carrier.

Like numerals of reference designate corresponding parts in the several figures of the drawings, and referring thereto 10 designates the frame of the machine, and 11 the main shaft, to which power is communicated in a suitable manner. A swinging carrier 12 is 55 arranged to carry labels from the holder 13 into labeling position, as shown in full lines in Fig. 1, and this carrier is operated by a segment 14, mounted on the rock-shaft 15, which is actuated through the medium of 60 arm 16 by a grooved cam 17 on the main shaft. The affixing devices 18 are carried by a rod 19, to which a vertical movement is imparted by the lever 20 on the rock-shaft. A holder-arm 21 is constructed and arranged to operate in a well-known manner to engage the label after it has been carried into position beneath the affixing devices by the carrier and hold it against the bottle 22 or other receptacle to permit the carrier to return for 7c another label and while the affixing devices are operating to affix the label.

Heretofore I have employed a spring operating on the support for the label-holder to carry the latter to the upward limit of its 75 movement and a cam device for lowering the holder, as disclosed in Letters Patents Nos. 647,043 and 674,141, granted to me on April 10, 1900, and May 14, 1901, respectively, and this construction operates satisfactorily with 80 a comparatively small supply of labels; but a larger supply cannot be used because the movement of the holder is limited by the character and size of the actuating-cam. By my present invention I am able to arrange a much 85 larger supply of labels in the holder than heretofore, thereby improving the operation of the machine and increasing its capacity.

The label-holder consists of a base-plate 23 and arms 28, carried by a supporting-tube 24, 90 which is guided in brackets 25 and 26 in the frame of the machine. The pile of labels 27 is held by the arms 28, which are offset at their lower ends and slotted at 29 to receive

the thumb-screws 30, whereby the arms can be adjusted in proper position on the base-plate. A feed-rod 31 is arranged to operate in the supporting-tube, and it carries a fol-
5 lower-plate 32 on its upper end, which pushes the pile of labels upward against the inwardly-projecting pins 33 at the upper ends of the arms 28, these pins being of sufficient length to prevent the label-pile from being pushed
10 out of the holder, yet permitting the carrier to disengage and carry away the top label from the pile. The holder is normally held down by a spring 34, arranged on the sup-
15 porting-tube between the bracket 26 on the frame of the machine and a bracket 35 at the bottom of the tube, and the holder is carried up so that the top label will contact with the carrier by a cam 36 on the main shaft, which
20 engages a lever 37, fulcrumed to the frame at 38 and connected with the supporting-tube of the holder at 39. The feed-rod is provided with a spring 40, which operates between the collar 41, fastened to the rod, near the top thereof, and a collar 42, fastened in the lower
25 end of the supporting-tube by a set-screw 43, the tension of this spring being exerted upon the follower to force the pile of labels to the top of the holder, and thereby insure that the top label in the pile will be in proper position
30 for contact with the carrier regardless of the number of labels in the pile.

To hold the pile of labels rigid at the time of contact with the carrier, I provide a gravity-pawl 44, pivoted at 45 to the bracket 35
35 and arranged to engage a screw-thread 46 on the lower portion of the feed-rod, so that as this rod is moved upward by its spring the pawl will ride over and engage the screw-thread and hold the rod against the pressure
40 thereon when the carrier and label-pile come in contact. I provide a handle 47 on the pawl for releasing it from engagement with the rod, so that the latter can be depressed to refill the holder with labels, and in order
45 to hold the rod down in its lowest position while the holder is being refilled I provide another pawl 48 for engagement with the threaded portion of the rod, Fig. 4. The two pawls 44 and 48 are preferably made integral, it be-
50 ing understood that the pawl 44 will fall by gravity into engagement with the threaded rod when the pawl 48 is released; but it is ap-
parent that the pawls may be constructed separately and the same results accomplished.
55 The paste-rolls 49 are supported in the paste-pot 50, which is reciprocated in ways 51 by a lever 52, which is pivoted to the frame at 53 and is actuated by an arm 54, controlled by the grooved cam 55, Fig. 6, this construc-
60 tion and operation being substantially similar to that described in my patents aforesaid. I also provide a bracket-arm 56, which is fastened to the frame and has its upper end bent at right angles and bifurcated, and the
65 bifurcated ends 57 shaped to receive and hold a paste-supply tank 58, which is pro-

vided with a faucet 59 at the bottom thereof. The tank is supported above the paste-pot, so that it will discharge directly into the pot when the latter is in the proper relative po-
70 sition without removing the latter from the machine.

In practice the handle 47 is depressed to release the pawl 44 from engagement with the feed-rod, and the latter is forced downward and locked by the pawl 48. The holder is then supplied with labels and the pawl 48 released, permitting the spring 40 to act on the feed-rod and follower to push the pile of labels up against the pins 33, and the pawl 80 44 thereupon falls by gravity into engagement with the rod and locks it. The machine being set in motion, the carrier swings backward in contact first with the paste-roll and then with the top label in the pile, the cam 85 36 acting on the lever 37 to carry the holder up against the tension of the spring 34, so that the top label will make proper contact with the carrier and adhere thereto at the part which has received paste from the paste-
90 roll. Meanwhile a bottle has been arranged in position on the rest 60, and the paste-pot has moved to rearward position and the carrier swings backward into position shown in full lines in Fig. 1, whereupon the holder-
95 arm descends to engage the label and press it against the bottle, while the carrier returns for another label and the affixing devices descend to affix the label to the bottle. When the carrier-arm begins to swing forward with
100 the label, the label-supply holder is carried downward by the spring 34, and this downward movement need be but very short and is limited by an adjustable stop 61 in the form of a collar on the supporting-tube, which
105 engages with the bracket 26 on the frame. The feed-rod is moved upward by its spring 40 as the labels are used, and the pawl 44 holds the rod in rigid position, so that proper contact can be made between the top label and
110 the carrier.

It is apparent that changes in the construction and arrangement of the invention may be made without departing from the spirit or sacrificing the invention, and I therefore re-
115 serve the right to make all such changes and embody the invention in all forms which fairly fall within its spirit and scope.

A label-holder of the character described may be constructed to receive a large num-
120 ber of labels, so that the machine may operate continuously for a long period without replenishing the supply. The parts may be constructed to hold a larger supply of labels than shown in the drawings, and the holder
125 and carrier may be changed to accommodate labels of different shapes. The intermit-
tent vertical bodily movement imparted to the holder by the cam 36 and arm 37 may be very slight and just sufficient to coöperate
130 with the carrier in disengaging the top label from the pile; but the movement of the feed-

rod is sufficient to push the pile of labels to the top of the holder until the very last label is removed by the carrier, thereby enabling a much greater supply of labels to be provided than would be possible if the intermittent bodily movement of the holder alone were depended upon for carrying the labels up in position for contact with the carrier. Instead of threading the lower portion of the feed-rod, as shown, I may provide any other kind of indentations with which the pawls may engage to lock the rod.

Having thus fully described my invention, what I claim, and desire to secure by Letters Patent, is—

1. In a labeling-machine, the combination of a label-holder comprising a base, upright arms fastened rigidly to the base and inclosing the label-pile, inwardly-projecting pins at the top of the arms, a carrier for removing the labels one at a time from the holder, means for imparting an intermittent vertical movement to the holder, and independent means constantly pressing against the bottom of the label-pile and forcing the top label against said pins.

2. In a labeling-machine, the combination with a label-holder, of a carrier for removing the labels one at a time from the holder, means actuated coincident with the carrier for imparting an intermittent vertical movement to the holder, independent means for feeding the pile of labels from the bottom of the holder to the top thereof, and a device for locking the feeding means against reverse movement.

3. In a labeling-machine, the combination with a label-holder, of a carrier for removing the labels one at a time from the holder, a feed-rod and means acting thereon to constantly press the pile of labels to the top of the holder, and a device constructed to permit the feeding movement of the rod and lock the rod against a reverse movement thereof when the top label and the carrier engage.

4. In a labeling-machine, the combination with a label-holder, of a carrier for removing the labels one at a time from the holder, a feed-rod and means acting thereon to constantly press the pile of labels to the top of the holder, and a pawl arranged to engage and lock the rod against reverse movement when the top label and the carrier engage.

5. In a labeling-machine, the combination with a label-holder, of a carrier for removing the labels one at a time from the holder, a feed-rod and means acting thereon to constantly press the pile of labels to the top of the holder, the lower portion of said rod being provided with a series of indentations, and a pawl arranged to engage the indentations to lock the rod against reverse movement when the top label and the carrier engage.

6. In a labeling-machine, the combination with a label-holder, of a feed-rod and means acting thereon to constantly press the pile of labels to the top of the holder, the lower por-

tion of said rod being provided with a series of indentations, a pawl operating to prevent reverse movement of the rod as it is fed upward, and a pawl for engaging said indentations to temporarily lock the rod and holder in lowered position.

7. In a labeling-machine, the combination with a label-supply holder, of a supporting-tube for the holder, a feed-rod arranged in said tube, a follower-plate on the upper end of the rod and within the holder, a spring surrounding the rod within the tube and acting to feed the rod and follower-plate upward against the pile of labels and constantly press the labels to the top of the holder and means for imparting an intermittent vertical movement to the holder.

8. In a labeling-machine, the combination with a holder, of a tube forming a support therefor, means for imparting an intermittent vertical movement to the holder and its support, a spring-pressed feed-rod arranged in the supporting-tube and constantly pressing the label-pile to the top of the holder, and a device carried by the supporting-tube and operating to lock the rod against reverse movement.

9. In a labeling-machine, the combination with a holder, of a tube forming a support therefor, a spring arranged on the supporting-tube for normally holding the holder in lowered position, means for intermittently raising the holder, a feed-rod operating in the supporting-tube to press the label-pile to the top of the holder, and a device carried by the supporting-tube for locking the feed-rod against reverse movement.

10. In a labeling-machine, the combination with a holder, of a tube forming a support therefor, means for imparting an intermittent vertical movement to the holder, a feed-rod operating in the supporting-tube, a follower carried at the upper end of the feed-rod, a collar on the rod near the top thereof, another collar at the lower end of the tube, a spring arranged on the rod within the tube and bearing at its ends against said collars to constantly press the rod and follower up against the label-pile and means for preventing reverse movement of the rod.

11. In a labeling-machine, the combination with a label-holder, of a feed-rod and means for operating the same, and two pawls arranged to separately engage the feed-rod, one to prevent reverse movement of the rod as it feeds upward and the other to temporarily prevent upward movement of the rod.

12. In a labeling-machine, the combination with a label-holder, of a tube forming a support therefor, a feed-rod arranged in said tube and means for operating the same, a bracket carried at the lower end of the tube, two pawls arranged to separately engage and lock the rod against reverse movement, and a single handle for releasing the pawls.

13. In a labeling-machine, the combination

with a label-holder and means for imparting an intermittent vertical movement thereto, of a feed-rod carried with the holder and arranged to press upon the bottom of the labels 5 to feed the labels to the top of the holder, means for feeding the rod, a pawl to engage the rod to prevent reverse movement thereof as it is fed upward, another pawl for engaging

the rod to hold it temporarily in lowered position, and a bracket carried with the holder 10 for supporting said pawls.
